(57) **CLAIM**

The ornamental design for a pan rack, as shown and described.

DESCRIPTION

FIG. 1 is a perspective view of a pan rack showing my new design.

FIG. 2 is a front view thereof;

FIG. 3 is a right view thereof;

FIG. 4 is a left view thereof;

FIG. 5 is a top view thereof;

FIG. 6 is a bottom view thereof; and,

FIG. 7 is a rear view thereof.

The broken lines in the drawings indicate unclaimed portions and form no part of the claimed design.
